[57] CLAIM

The ornamental design for a wheel cover front face, as shown and described.

DESCRIPTION

FIG. 1 is a perspective view of a wheel cover front face showing my new design;

FIG. 2 is a front elevational view thereof; and,

FIG. 3 is a right side elevational view thereof; left side elevational view being a mirror image.

Top and bottom plan views are similar to FIG. 3.

The broken line showing of a wheel rim in FIGS. 1 and 3 of the drawing is for illustrative purposes only and forms no part of the claimed design.

FIG. 1.

FIG. 2.

FIG. 3.
